(57) **CLAIM**

The ornamental design for a display structure, as shown and described.

DESCRIPTION

FIG. 1 is a top right perspective view of a display structure showing our new design;

FIG. 2 is a bottom left perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the display structure or environment that form no part of the claimed design.

The oblique shade lines in the figures show transparency or translucency.

1 Claim, 6 Drawing Sheets
